AIR CONDITIONING APPARATUS

Edward W. Roessler, Schenectady, N. Y., assignor
to General Electric Company, a corporation of
New York

Application July 27, 1934, Serial No. 737,218

26 Claims. (Cl. 257—9)

My invention relates to air conditioning apparatus.

An object of my invention is to provide an improved unit room air conditioning apparatus which produces even distribution of air in the room, which can be readily manufactured, assembled and installed, and in which the working parts are readily accessible.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is a front elevation partly in section of an air conditioning apparatus embodying my invention; Fig. 2 is a plan view partly in section of the apparatus shown in Fig. 1; Fig. 3 is an enlarged sectional view on the line 3—3 of Fig. 1; Fig. 4 is a detail view of the mechanism for operating the outlet louvers shown in Figs. 1 and 3; Fig. 5 is a partial side elevation partly broken away, showing another arrangement for operating the outlet louvers, the outer casing being removed from the apparatus; Fig. 6 is a further modification of the louver operating mechanism; and Fig. 7 is a perspective view, partly in section, of the inner casing construction shown in Figs. 1 to 3.

Referring to the drawings, the air conditioning apparatus shown and described herein comprises an inner casing 10 and an outer casing 30 spaced apart to provide an air mixing chamber 30a. Both fresh air and air from the room to be conditioned are admitted to the mixing chamber, the fresh air being admitted at the rear through a damper controlled opening 25, and the room air being admitted at the ends of the apparatus through louvers 33 and openings 34. The inner casing is provided with blowers 12 which draw air through filters 22 and 23 covering openings 20 at both ends and through the top of the casing and circulate it through a U-shaped duct 17a formed by a baffle 17 extending longitudinally through the center of the casing. Heat exchange elements comprising heating coils 44 and cooling coils 47 and a humidifying pan 60 are arranged in the U-shaped duct to condition the air passing therethrough. The conditioned air is discharged at the front of the casing through aligned openings 19 and 31. In the discharge opening 19 at the front of the inner casing is arranged a shutter mechanism 78 which operates normally to direct

the air upwardly and which directs the air downwardly when it is being heated.

Referring now to Figs. 1, 2, 3 and 7, I have shown an air conditioning apparatus of the type used to condition the air in rooms, and ordinarily to be arranged in the room to be conditioned. The apparatus includes an inner casing 10, which is supported above the floor on legs 11. This casing, which is shown in perspective in Fig. 7, is of a rectangular form, open at the top, and closed at the bottom by a base 62, which serves as a drain pan. One end only of the apparatus is shown in section in Fig. 1; however, the ends are similar and symmetrical, except that the various connections for admitting heat exchanging medium to the heating and cooling elements are located at the end shown in section. Within the casing 10 are two fans or blowers 12 arranged on either side of a motor 13 and driven by the motor. The blowers are supported within the casing on a partition 14, which is attached to brackets 15 and 16 secured to the side walls of the casing, and dividing the casing into upper and lower chambers. The lower chamber is provided with a partition or baffle 17 extending across the chamber parallel to the front of the casing and dividing the chamber so as to form a U-shaped duct. This duct has inlet openings 18 in the partition 14 to provide communication at one end with the blowers 12, and an outlet opening 19 in the front wall of the casing 10 through which air is discharged into the room. The upper chamber, which is open at the top, is provided with circular openings 20 at each end. Filters 22 and 23 of glass wool, or other suitable material, are placed over the openings 20, and over the open top of the casing 10, respectively, to clean the air and prevent dust and other foreign matter from entering the inner casing. The rear wall 24 of the inner casing is extended upwardly from the casing and is provided with an opening 25 and with a fresh air duct 26 communicating with the opening. This fresh air duct has an adjustable portion 27 arranged to extend through a window or other opening in the wall of the room. A wall plate 28 which may be fitted flush with the outer wall of the building is secured to the outer end of the adjustable portion 27 and a rain-shield 29 extends outwardly from the plate.

An outer casing 30, which is open at the rear and bottom, surrounds the inner casing in spaced relation to provide a chamber or air space between the inner and outer casings at the top and sides thereof. The upper portion and sides of the casing 30 fit closely about the extended rear wall of 55

the inner casing. This outer casing may readily be removed to gain access to the inner casing and the working parts of the air conditioning apparatus. The outer casing extends nearer the inner casing at the front than at the sides and is provided with an opening 31 having a frame 32 registering with the outlet opening 19 of the inner casing. The outer casing is also provided with fixed louvers 33 at either end thereof through which room or recirculated air may be admitted. Room air may also enter the chamber between the casings through an opening 34 at the rear sides of the chamber between the casings and below the extended portion of the rear wall 24.

15 The height of the inner casing above the floor may be adjusted by turning threaded portions 35 of the legs 11 to change the length of the legs and then locking them in place by threaded nuts 35a. In this manner the position of the fresh air duct 26 may be adjusted to the height of a window or other opening in the wall of the room. In order that the outer casing 30 may be adjusted to the proper height with respect to the inner casing, it is provided with a base made of a plurality of stacked channel strips 36 which are removable and any number of which may be employed to secure the proper height of the casing above the floor. Each of the strips 36 comprises a channel bent in U-shaped form so as to lie along the base of the side and front walls of the casing and provided with angles 37 welded to the channels to secure them in assembled relation. When the proper height of the cabinet has been determined the angles 37 may be bent over, or 35 the strips 36 may be otherwise secured to each other to provide a rigid base.

When the fans 12 are in operation air is drawn from out-of-doors through the duct 26, and from the room through the louvers 33 and into the space or chamber between the inner and outer casings from which the air passes through the filters 22 and 23 into the upper or blower chamber as indicated by arrows in Fig. 7. The air then enters the blowers 12 and is forced through the openings 18 into the lower chamber, passes around the baffle 17, and out through the openings 19 and 31 in the inner and outer casings respectively. The amount of fresh air admitted may be varied by changing the position of a damper 37 which is 50 pivotally mounted in the fresh air opening 26 on the pins 38 at the ends of the opening. The damper may be operated from the front of the casing by turning a knob 39 mounted on a shaft 40, and connected to operate the damper through 55 a link 41, a door 42 being provided in the outer casing 30 to afford access to the knob 39.

The air passing through the inner casing may be either heated or cooled according to the requirements of the room to be conditioned. In 60 the construction illustrated a heating element 43 comprising a plurality of steam or hot water coils 44 having fins 45 thereon is arranged in the rear portion of the lower U-shaped chamber, and a cooling element 46 comprising a plurality of refrigerant coils 47 having fins 48 thereon is arranged in the front portion of the lower U-shaped chamber, the baffle 17 extending between the heating and cooling elements. Thus, when air is circulated by the blowers 12, it passes downwardly 65 over the heating element and upwardly over the cooling element. The connections and valves for the heating and cooling elements may conveniently be placed in the space between the inner and outer casings at one end of the inner casing, 70 as clearly shown in Fig. 1. In the construction

shown, a heating medium such as steam or hot water is supplied to the coils 44 from any suitable source through a conduit 49, and the quantity thereof is regulated by a valve 50 which is controlled by a solenoid 51, or other suitable device operated by a thermostat arranged in the room to be conditioned. Refrigerant is supplied to the cooling element 46 through a conduit 52, the quantity of refrigerant supplied being regulated by an automatic valve 53, which is connected to the refrigerant coils 47 by a conduit 54. The valve 53 is arranged to maintain a constant predetermined temperature in the coils 47, and, for this purpose, may be provided with expandible bellows communicating through a tube 17 55 (like that shown in Fig. 5) to a bulb containing a volatile liquid and arranged to respond to the temperature of the coils 47. Gaseous refrigerant is removed from the coils 47 through a connection 56 and is returned to the source. The supply of refrigerant to the valve 53 may be regulated by a thermostat responsive to the temperature of the room to be cooled.

Either the heating element 43 or the cooling element 46 may be placed in operation by a 25 manual control arranged on the inner casing. When the apparatus is set for heating the source of heating fluid is regulated by a thermostat responsive to room temperature, and when the apparatus is set for cooling the source of refrigerant 30 is regulated by the same thermostat responsive to room temperature. Only one of the elements may be set for operation at any given time. The manual control for selecting the heating or cooling operations includes a knob 57 arranged on a panel 35 58 together with the damper control knob 39 on the front of the inner casing. A third knob 59, indicated in dotted lines in Fig. 1, may be provided to regulate the operation of the fan motor 13. All of these knobs are accessible through the 40 door 42 in the outer casing 30.

When the air passing through the apparatus is being heated it is humidified by passing over a body of water contained within a tray 60 extending between the sides of the inner casing 45 immediately beneath the heating coils 44 and resting on brackets 61 at the ends of the inner casing. Water is supplied to this tray, only, during the heating operation, through a control valve from any suitable source of supply, such as 60 the water system of the building in which the apparatus is installed. Any overflow of water from the tray 60 will flow into the bottom 62 of the casing 10 within a base 63 and out of the casing through a drain connection 64 in the bottom 55 of the casing. Any water vapor condensing on the cooling coils 47 will also fall into the bottom 62 of the casing and flow through the drain 64.

From the foregoing it is apparent that the apparatus illustrated will supply either cooled or heated air as desired. The heated air will naturally tend to rise on leaving the outlet while the cooled air will fall toward the floor. Therefore, when the apparatus is being used to cool the 65 room there will be a tendency for the freshly cooled air to remain in the lower part of the room, and when the apparatus is being used to heat the room there will be a tendency for the freshly heated air to rise to the upper portion 70 of the room, and thereby prevent a proper mixing of the conditioned air and the air within the room. In order to avoid this undesirable condition, I provide an arrangement whereby the cooled air is directed into the upper portion of 75

the room and the heated air is directed toward the floor. In this manner, there is a forced circulation of the air supplied to the room away from that portion of the room toward which it naturally tends to move, and there is therefore a complete mixing of the conditioned air and the air in the room.

In the construction illustrated I provide a plurality of arcuate louvers or deflectors 65, which are arranged longitudinally of the opening 19, and which may be moved into either of two positions selectively to direct the air either upwardly or downwardly from the outlet opening. Each of the louvers is provided with triangular ears 65a at its opposite ends pivoted on pins 66 secured to inturned flanges 67 at the ends of the opening. These louvers are linked together by a bar 68 pivoted at 69 to the ends of the ears 65a, so that the louvers may be moved in unison. When the louvers 65 are in the position shown in Fig. 3, the air passing outwardly through the opening 19 is directed upwardly. This is the normal position for the louvers when the air passing through the apparatus is not being heated. When the air is heated the louvers 65 are shifted on the pivots 66 so that the air leaving the opening 19 is directed downwardly, one of the louvers being shown in this position in Fig. 6. Any suitable device may be provided for shifting the louvers to change the direction of the air discharged through the outlet 19. This device may be either manual or automatic. However, I prefer to provide an arrangement whereby the louvers are normally biased to a position for directing the air upwardly and including an automatic mechanism which will operate to shift the louvers and direct the air downwardly whenever the air is being heated.

In the construction illustrated in Figs. 1 to 4 an automatic-heat responsive device 70 is located at one side of the opening 19. This device is clearly shown in detail in Fig. 4, and includes an expandible bellows filled with a volatile liquid, and links 72 and 73 comprising a lever system biased to a position for holding the louvers 65 so as to direct the air upwardly as it is discharged from the opening 19. This device is mounted on a bracket 74 at one side of the opening 19 so that the bellows 71 is located in the stream of air passing through the apparatus and out through the discharge opening 19. The link 72 is pivoted to the bracket 74 at 75, and the link 73 is pivoted to the link 72 at 76 and is connected to the lowermost louver by a pin 69 engaging a slot 77 in the link 73 to provide a sliding connection. In the position shown in Fig. 4 the link 72 is held against the stop 78 by a helical compression spring 79 arranged between a support 80 secured to the bracket 74 and a flange 81 on the link 72. The link 73 is held against a stop 82 by an over-center tension spring 83 connected to the end 84 of the link 73 and to an arm 85 extending downwardly from the support 80. In this position the link 73 holds the pin 69 on the louver 65 in its uppermost position and the air passing through the opening 19 is directed upwardly. The bellows 71 is secured to the bracket 74 by a bolt 71a and is provided with a pin 86 seated on an upturned portion 87 of the flange 81 of the link 72. When the air passing through the apparatus is heated to a predetermined degree the liquid in the bellows 71 vaporizes and expands the bellows, thereby rotating the link 72 in a clockwise direction about the pin 75 against the force of the spring 79 until the link engages

a stop 88. As the link is rotated, the pivot 76 passes over the center of spring 83, which snaps the link 73 downwardly against a stop 89, and thereby rotates the louvers 65 about the pivots 66. The louvers now direct downwardly the air passing outwardly through the opening 19. The louvers will be maintained in this position as long as the temperature of the air remains above a predetermined value. When the temperature is lowered again below this value the bellows 71 will contract and the spring 79 will rotate the link 72 in a counter-clockwise direction about the pivot 75 and return the device to the position shown in Fig. 4. This arrangement therefore operates automatically to maintain a proper circulation of air within a room whether the air passing through the apparatus is being heated, cooled or merely circulated, and uneven temperatures about the room are thereby prevented.

In Fig. 5 is shown another device for controlling the shifting of the louvers in the outlet-opening. The device here illustrated comprises a lever 90 pivoted at 91 to a stationary arm 92 secured to a bracket 93 on the outer wall of the inner casing 10. An offset portion 90a of the lever 90 extends through an opening 90b in the casing and is connected by a slot 94 and a pin 95 to the bar 68 which operates the louvers 65. The lever 90 is held by a tension spring 96 in a position so that the louvers 65 direct the air upwardly. An expandible bellows 97 supported on the bracket 93 and secured to the lever 90 by a bolt 98 communicates through a tube 99 with a bulb containing a volatile liquid and arranged within a cap 100 in contact with one of the heating coils. When the coils 44 are heated liquid vaporizes in the bulb and is discharged through the tube 99 to the bellows 97 which expands and rotates the lever 90 about the pivot 91. This moves the bar 68 downwardly and shifts the louvers 65 so that the air discharged through the outlet is direct downwardly. In order to move the lever 90 with a snap action there is provided an over-center compression spring 101 mounted on a rod 102 which is loosely mounted in lugs 103 and 104 secured on the lever 90 adjacent the portion 90a and on the wall of the casing respectively. It is apparent that, in this arrangement, when the coils 44 are heated the bellows 97 will expand and shift the louvers 65 to direct the heated air downwardly toward the floor of the room.

Under some conditions of operation it may be desirable to arrange the automatic control for shifting the direction of the air discharged from the outlet of the conditioning apparatus, so that the air will be directed downwardly only when the control of the heating element is set for heating and the air is being heated. In order to accomplish this, I provide an arrangement such as that shown in Fig. 6. In the construction illustrated the control device is in position for directing the heated air downwardly. This control comprises a bellows 105, shown in its expanded position, mounted in a bracket 106 which may be secured to the wall of the casing in a position similar to that of the device 70 shown in Fig. 3. The bellows is arranged to actuate the bar 68 through a bell-crank 107 to which it is connected by a bolt 108. The bellows 105 may be actuated to expand and move the louvers to the position shown only when the air circulated within the ducts of the apparatus is above a predetermined temperature. This is accomplished by providing a thermostat such as a bimetallic strip 109 in the path of the air circulated in the front 75

portion of the U-shaped duct of the unit, and by connecting the thermostat in a circuit including a switch 110 which is closed only when the heat supply valve 50 is opened. When the circuit is closed by operation of the thermostat 109 and the switch 110, a heating filament 111 arranged within a closed vessel or boiler 112 filled with some suitable fluid is heated by the passage of current. This vaporizes or expands the fluid contained within the vessel 112 and it is discharged through a connection 113 into the bellows 105 which expands to operate the bell-crank and shift the louvers so that the louvers are in the position shown in Fig. 6 and discharge the air downwardly. The valve 50 may be controlled by a room thermostat which will operate a solenoid 114 to open the valve and close the switch 110 whenever heat is required. When the control circuit is opened, either by opening of the thermostat 109, or of the switch 110, the filament 111 will be disconnected and the fluid cooled. The bellows 105 will contract and rotate the bell-crank 107 in a clockwise direction, raise the pin 68 and shift the louvers 65 so that air discharged from the outlet will be directed upwardly. It is evident that this device will operate to shift the louvers to direct the air downwardly only when the thermostat in the air duct is closed and at the same time the heat supply valve is open.

During operation of the air conditioning apparatus illustrated the proportion of recirculated air drawn through the louvers 33 and opening 34, and fresh air supplied through the duct 29 is controlled by operation of the damper 37. The recirculated air and fresh air mix more or less in the space between the inner casing 10 and the outer casing 30 and are drawn by the blowers 12 into the upper chamber of the casing 10, and from thence are forced by the blowers into the lower portion of the chamber around the baffle 17 over the heating element 43, upwardly around the cooling element 46 and out through the opening 19 in the front of the cabinet. If the heating element 43 is not in operation the air discharged from the outlet 19, whether cooled or not, will be directed upwardly by the louvers 65. If the heating element is in operation and the air is being heated thereby, the louvers will automatically be shifted to discharge the air downwardly. By this arrangement a very satisfactory circulation of air within the room is maintained together with a proper mixing of the room air and conditioned air. The apparatus thus provides more even temperatures throughout the room and prevents cold draughts from circulating about the floor.

It is apparent from the foregoing that I have provided an improved air conditioning apparatus having an outlet which directs the conditioned air upwardly into the room unless it is being heated when it is directed downwardly, thereby providing the greatest possible comfort for the occupants of the room by insuring even temperatures and a proper circulation of air. Furthermore all parts of the device are readily accessible, and the construction is simple and rugged.

While I have shown my invention as embodied in an air conditioning unit, other applications will readily be apparent to those skilled in the art. I do not, therefore, desire my invention to be limited to the particular construction shown and described, and I intend in the appended claims to cover all modifications within the spirit and scope of my invention.

What I claim as new and desire to secure by Letters Patent of the United States is:

1. An air conditioning apparatus including a duct having an outlet, means for circulating air through said duct and for discharging air therefrom through said outlet, means for heating air circulated through said duct, and means for normally directing upwardly the air discharged from said duct, said means being responsive to a predetermined heating of the air circulated through said duct for directing downwardly the air discharged therefrom. 5

2. An air conditioning apparatus including a casing having an inlet and an outlet, means for circulating air through said casing and for discharging air therefrom through said outlet, means for heating the air within said casing, and means for normally directing upwardly the air discharged from said outlet, said means being responsive to a predetermined degree of heating 10 of the air in said casing for directing downwardly the air discharged from said outlet. 15

3. An air conditioning apparatus including a casing having an inlet and an outlet, means for circulating air through said casing and for discharging air therefrom through said outlet, means including a pivoted deflector for directing upwardly the air discharged from said outlet, means for heating the air within said casing, and means responsive to a predetermined degree of 20 heating of the air in said casing for shifting said deflector so as to direct downwardly the air discharged from said outlet. 25

4. An air conditioning apparatus including a casing having an inlet and an outlet, means for circulating air through said casing and for discharging air therefrom through said outlet, means including a plurality of deflectors for directing upwardly the air discharged from said outlet, means for heating the air within said casing, and means responsive to a predetermined degree of heating of the air circulated through 30 said casing and including a linkage connecting said deflectors for shifting said deflectors so as to direct downwardly the air discharged from 35 said outlet. 40

5. An air conditioning apparatus including a casing having, front, back and side walls, an air inlet for said casing, an air outlet in the front wall of said casing, means for circulating air 50 through said casing and for discharging air therefrom through said outlet, means including a plurality of deflectors for directing upwardly the air discharged from said outlet, means for heating the air within said casing, and means 55 responsive to a predetermined degree of heating of the air in said casing for shifting said deflectors so as to direct downwardly the air discharged from said outlet.

6. An air conditioning apparatus including a 60 casing having an inlet and an outlet, a duct in said casing connecting said inlet and said outlet, a heater in said duct, a cooling element in said duct, means for circulating air through said duct and for discharging air from said outlet, means 65 for directing upwardly the air discharged from said outlet, and means responsive to a predetermined temperature of the air in said casing for directing downwardly the air discharged from said outlet. 70

7. An air conditioning apparatus including a casing having an inlet and an outlet, a duct in said casing connecting said inlet and said outlet, a heating element in said duct, a cooling element in said duct, means for circulating air through 75

said duct and for discharging air from said outlet, means for directing upwardly the air discharged from said outlet, and means responsive to a predetermined degree of temperature in said heating element for directing downwardly the air discharged from said outlet.

8. An air conditioning apparatus including a casing having an inlet and an outlet, a U-shaped duct in said casing connecting said inlet and said outlet, a heating element arranged in one leg of said duct, a cooling element arranged in the other leg of said duct, means for circulating air through said duct and for discharging the same from said outlet, means for directing upwardly the air discharged from said outlet, and means responsive to a predetermined degree of heating of the air in said casing for directing downwardly the air discharged from said outlet.

9. An air conditioning apparatus including a casing having an inlet and an outlet, a U-shaped duct in said casing connecting said inlet and said outlet, a heating element arranged in one leg of said duct, a cooling element arranged in the other leg of said duct, means for circulating air through said duct and for discharging air from said outlet, means for directing upwardly the air discharged from said outlet, and means including a snap-acting lever responsive to a predetermined degree of heating of the air in said casing for directing downwardly the air discharged from said outlet.

10. An air conditioning apparatus including an inner casing having an inlet and an outlet, an air filter covering the inlet in said inner casing, an outer casing surrounding said inner casing and forming a chamber between said casings, said outer casing having an opening registering with the outlet in said inner casing, means for admitting air to said chamber, means arranged within said inner casing for circulating air from said chamber through said inner casing and for discharging air through said outlet, and means arranged within said inner casing for varying the temperature of the air circulated therethrough.

11. An air conditioning apparatus including an inner casing having an inlet and an outlet, an air filter covering said inlet, an outer casing surrounding said inner casing and forming a chamber between said casings, means for admitting fresh air to said chamber, means for admitting recirculated air to said chamber, said outer casing having an outlet registering with the outlet in said inner casing, means for circulating air from said chamber through said inner casing and for discharging said air through said outlet, and means for varying the temperature of the air circulated through said inner casing.

12. An air conditioning apparatus including a casing having an extension on one wall thereof and having an inlet and an outlet, an air filter covering said inlet, a second casing surrounding said first mentioned casing and cooperating with said extended wall to form a chamber between said casings, means including an opening in said extended wall for admitting air to said chamber, means arranged within said first mentioned casing for discharging air therefrom through said outlet, and means arranged within said first mentioned casing for varying the temperature of the air discharged therefrom.

13. An air conditioning apparatus including a casing having an extension on one wall thereof and having an inlet and an outlet, an air filter

covering said inlet, a second casing surrounding said first mentioned casing and cooperating with said extended wall to form a chamber between said casings, means including an opening in said extended wall for admitting fresh air to said chamber, means including an opening in said second casing for admitting recirculated air to said chamber, means arranged within said first mentioned casing for discharging air therefrom through said outlet, and means arranged within said first mentioned casing for varying the temperature of the air discharged therefrom.

14. An air conditioning apparatus including a casing having an extension on one wall thereof and having an inlet and an outlet, an air filter covering said inlet, a second casing surrounding said first mentioned casing and cooperating with said extended wall to form a chamber between said casings, means including an opening in said extended wall for admitting fresh air to said chamber, means including an opening in said second casing for admitting recirculated air to said chamber, means arranged within said first mentioned casing for discharging air therefrom through said outlet, means for controlling the quantity of fresh air admitted to said chamber, and means arranged within said first mentioned casing for varying the temperature of the air discharged therefrom.

15. An air conditioning apparatus including a casing having an extension on one wall thereof and having an inlet and an outlet, an air filter covering said inlet, a second casing surrounding said first mentioned casing and cooperating with said extended wall to form a chamber between said casings, means including an opening in said extended wall for admitting fresh air to said chamber, means including an opening in said second casing for admitting recirculated air to said chamber, means arranged within said first mentioned casing for discharging air therefrom through said outlet, means for controlling the quantity of fresh air admitted to said chamber, means including a heating element and a cooling element arranged within said first mentioned casing for varying the temperature of the air discharged therefrom, means for normally directing upwardly the air discharged from said outlet, and means responsive to a predetermined degree of heating of the air circulated within said first mentioned casing for directing downwardly the air discharged from said outlet.

16. An air conditioning apparatus including a casing having an air inlet and an air outlet, a fresh air intake duct secured to said casing, means arranged within said casing for discharging air therefrom through said outlet, means arranged within said casing for varying the temperature of the air discharged therefrom, means arranged to adjust the height of said casing above the floor on which it rests for varying the height of said duct above said floor, a second casing surrounding said first mentioned casing and forming a chamber between said casings, and means for adjusting the height of said second casing to conform with the height of said first casing.

17. An air conditioning apparatus including a casing having an air inlet and an air outlet, a fresh air intake duct secured to said casing, means arranged within said casing for discharging air therefrom through said outlet, means arranged within said casing for varying the temperature of the air discharged therefrom, means arranged to adjust the height of said casing above

- floor on which it rests for varying the height of said duct above said floor, a second casing surrounding said first mentioned casing and forming a chamber between said casings, and means including a plurality of detachable strips at the base of said second casing for adjusting the height of said second casing to conform with the height of said first casing.
18. An air conditioning apparatus including a plurality of walls and having an air inlet and an air outlet, one of the walls of said casing being extended above said casing, a fresh air intake duct secured to the extended portion of said one wall, means arranged within said casing for discharging air therefrom through said outlet, means arranged within said casing for varying the temperature of the air discharged therefrom, means for adjusting the height of said casing above the floor on which it rests for varying the height of said duct above the floor, a second casing surrounding said first mentioned casing and cooperating with said extended wall to form a chamber between said casings, and means including a plurality of detachable strips at the base of said second casing for adjusting the height of said second casing to conform with the height of said first casing.
19. An air conditioning apparatus including a casing having front, side and rear walls, an air inlet in said casing, an air outlet in the front wall of said casing, the rear wall of said casing being extended upwardly and having an opening therein, a fresh air intake duct secured to said rear wall and communicating with the opening therein, means arranged within said casing for discharging air therefrom through said outlet, means arranged within said casing for varying the temperature of the air discharged therefrom, means arranged to adjust the height of said casing above the floor on which it rests for varying the height of said duct above said floor, a second casing comprising front, side and top walls and cooperating with the rear wall of said first mentioned casing to form a chamber between said casings, said second casing having an outlet opening corresponding with the air outlet in said first mentioned casing and communicating therewith, and means for adjusting the height of said second casing to conform with the height of said first casing.
20. An air conditioning apparatus including a casing, means for circulating air through said casing and for discharging air therefrom, means for selectively directing the air discharged from said casing in an upward direction or in a downward direction, said last mentioned means being arranged normally to direct the air discharged from said casing in one of said directions, means including a heat exchange element arranged within said casing for varying the temperature of the air therein, means for admitting a heat exchanging medium to said element, and means responsive to the admission of heat exchanging medium to said element for operating said selective directing means to direct the air discharge from said casing in the other of said directions.
21. An air conditioning apparatus including a casing, means for circulating air through said casing and for discharging air therefrom, means for selectively directing the air discharged from said casing in an upward direction or in a downward direction, said last mentioned means being arranged normally to direct the air discharged from said casing in one of said directions, means including a heat exchange element arranged within said casing for varying the temperature of the air therein, means for admitting a heat exchanging medium to said element, and means responsive to the admission of heat exchanging medium to said element for operating said selective directing means to direct the air discharged from said casing in the other of said directions.
22. An air conditioning apparatus including a casing, means for circulating air through said casing and for discharging air therefrom, means for selectively directing the air discharged from said casing in an upward direction or in a downward direction, said last mentioned means being arranged normally to direct the air discharged from said casing in one of said directions, means including a heat exchange element arranged within said casing for varying the temperature of the air therein, and means dependent upon a predetermined range of temperature of the air circulated through said casing for operating said selective directing means to direct the air discharged from said casing in the other of said directions.
23. An air conditioning apparatus including a duct having an outlet, means for circulating air through said duct and for discharging air therefrom through said outlet, a heating element arranged in said duct, means for admitting a heating medium to said heating element, means for controlling said heating medium admitting means, means for normally directing upwardly the air discharged from said outlet, said last mentioned means being dependent upon operation of said control means to admit heating medium to said heating element for directing downwardly the air discharged from said outlet.
24. Apparatus for conditioning the air within an enclosure including a casing, means for circulating air through said casing and for discharging air therefrom, means for selectively directing the air discharged from the air discharged from said casing toward the upper portion of said enclosure or toward the lower portion of said enclosure, said last mentioned means being arranged normally to direct the air discharged from said casing toward one of said portions of said enclosure, means including a heat exchange element arranged within said casing for varying the temperature of the air therein, and means dependent upon a predetermined range of temperature of the air circulated through said casing for operating said selective directing means to direct the air discharged from said casing toward the other of said portions of said enclosure.
25. Apparatus for conditioning the air within an enclosure including a casing, means for circulating air through said casing and for discharging air therefrom, means for selectively directing the air discharged from said casing toward the upper portion of said enclosure or toward the lower portion of said enclosure, said last mentioned means being arranged normally to direct the air discharged from said casing toward one of said portions of said enclosure, means including a heat exchange element arranged within said casing for varying the temperature of the air therein, means for admitting a heat exchanging medium to said element, and means responsive to the admission of heat exchanging medium to said element for operating said selective directing means to direct the air discharged from said casing toward the other of said portions of said enclosure.

26. Apparatus for conditioning the air within an enclosure including a casing, means for circulating air through said casing and for discharging air therefrom, means for selectively directing the air discharged from said casing toward the upper portion of said enclosure or toward the lower portion of said enclosure, said last mentioned means being arranged normally to direct the air discharged from said casing toward one of said portions of said enclosure, means including a heat exchange element ar-
5 ranged within said casing for varying the temperature of the air therein, means for admitting a heat exchanging medium to said element, means for controlling said heat exchanging medium admitting means, and means responsive to the operation of said controlling means for operating said selective directing means to direct the air discharged from said casing toward the other of said portions of said enclosure. 5
